CLAIM

The ornamental design for a solar powered flashlight case, as shown.

DESCRIPTION

FIG. 1 is a perspective view of the solar powered flashlight case of the present invention in an opened position;

FIG. 2 is an alternate perspective view thereof;

FIG. 3 is a top plan view thereof;

FIG. 4 is a front elevation view thereof;

FIG. 5 is a right side elevation view thereof;

FIG. 6 is a left side elevation view, thereof;

FIG. 7 is a perspective view of the solar powered flashlight case of the present invention in a closed position;

FIG. 8 is a top plan view thereof;

FIG. 9 is a front elevation view thereof;

FIG. 10 is a right side elevation view, the left side elevation view being a mirror image thereof; and,

FIG. 11 is a rear elevation view thereof.

The broken lines are shown in the views for illustrative purposes only and form no part of the claimed design.
